CLAIM

The ornamental design for a medical gown, as shown and described.

DESCRIPTION

FIG. 1 is an environmental, perspective view of the medical gown according to the invention;

FIG. 2 is a front elevational view of the medical gown as shown in FIG. 1;

FIG. 3 is a left side view of the medical gown as shown in FIG. 1, wherein the right side view is a mirror image of the left side view;

FIG. 4 is a rear elevational view of the medical gown as shown in FIG. 1;

FIG. 5 is a top plan view of the medical gown as shown in FIG. 1 thereof;

FIG. 6 is a bottom plan view of the medical gown as shown in FIG. 1 thereof; and,

FIG. 7 is a front elevational view of the medical gown of FIG. 1 shown in an open position.

The broken lines shown in FIG. 1 that show the outline of a human body do not form part of the claimed design, whereas the dashed lines shown on the medical gown in FIGS. 1, 2 and 4-7 represent stitches and do form part of the claimed design.
